UNITED STATES PATENT OFFICE

ABRAHAM L. MOLER, OF RICHMOND, VIRGINIA, ASSIGNOR OF ONE-HALF TO JOHN W. SMALL, OF RICHMOND, VIRGINIA

GREASE CELLAR

Application filed May 21, 1927, Serial No. 193,296. Renewed July 23, 1930.

This invention relates to improvements in grease cellars.

One object of my invention is to provide an improved grease cellar for locomotive driving boxes, wherein provision is made for automatically dispensing the grease or other lubricant to the journal, in combination with provision for effective self-clearing of the grease cellar with respect to the used or waste lubricant to the end that a minimum of attention is required to maintain the cellar in proper condition.

Another object of my invention is to provide a grease cellar for locomotive driving boxes, wherein the cellar is provided with a central-dispensing chamber and side collecting chambers, the latter being provided with means for automatically disposing of the carried over or waste lubricant collected therein, the disposal of the waste lubricant being effected in part, by pressure automatically.

Other objects of my invention are to provide a grease cellar which is comparatively light in weight; economical to manufacture; efficient in operation; and which has adequate provisions for maintaining the same cool when in position in the driving box.

In the drawing forming a part of this specification, Figure 1 is an inside elevational end view of a locomotive driving box showing my improvements in connection therewith, the journal being shown in section. Figure 2 is a top plan view of the grease cellar proper. Figure 3 is a longitudinal, vertical section corresponding to the line 3-3 of Figure 2. And Figure 4 is a transverse, vertical sectional view corresponding to the line 4-4 of Figure 2.

In said drawing, a driving box for a locomotive of well known construction is indicated at A, the same having depending spaced parallel jaws 10-10 between which the grease cellar is adapted to be interposed and the usual bearing brass 11. The grease cellar proper, as shown, preferably comprises a casting with a central-dispensing chamber 12 and two side or lateral collecting chambers 13-13. The central chamber 12 is defined by a bottom wall 14 of relatively narrow width, vertical side walls 15-15 and an integral

end wall 16. In this chamber, the grease dispensing means are provided, the same comprising a perforated grease-dispensing plate 17; a cake of grease 18; a follower 19 in the form of a plate; and springs 20 to yieldingly force the follower 19 upwardly and, in turn, the grease cake and plate 17. The plate 17 conforms approximately in width to the width of the central chamber 12 so that it only extends over a relatively small arc of the journal. The upper main portion of the plate 17 is conformed to the curvature of the journal and has depending side flanges 21-21 which slide between and are guided by the upper portions of the vertical side walls 15, the inner faces of the latter being recessed or rabbeted so as to define bottom shoulders 22-22 to limit the downward movement of the plate 17, as will be understood. Telltales or indicators 23 are secured to the follower plate 19 and are extended downwardly through openings 24 in the bottom wall of the casting so that the condition of the grease cake may be ascertained from mere observation without taking down the cellar. The telltales also are used to pull down the follower plate when renewing the grease cake.

Each of the side collecting chambers 13 is defined by a curved bottom wall or web 25, the latter having the upper portion 26 thereof extended vertically, and integral arcuate end walls 27 and 28. Said bottom wall 25 merges with the corresponding vertical side wall 15 at a point slightly below the top edge of the latter so as to make the collecting chambers 13 shallow as compared with the dispensing chamber 12. The upper edges of the end walls 16, 27 and 28 are made on a radius corresponding to that of the journal and normally located closely adjacent thereto so as to provide an effective dust guard.

The inner end of the chamber 12 is normally closed by a closure plate 29 attached to the main casting by two bolts 30, which pass through vertically elongated slots 31 in the plate 29 so that, by loosening the bolts 30, the plate 29 may be dropped down sufficiently to permit insertion or removal of the grease cake.

The grease cellar casting is also provided

with four corner lugs 32—32, each of which has an aperture 33 therethrough, so that the grease cellar may be supported in position by a pair of elongated bolts 34, which are passed through said apertures 33 and corresponding alined apertures in the lower portions of the jaws 10 of the driving box. The bolts 34 may be held in position by cotters 35. To brace the corner lugs, arcuate corner webs 36 are provided uniting the same with the central portion of the casting and also vertical reinforcing webs 37 are provided, uniting the lugs and the laterally extended sections 25 of the side chambers as clearly indicated in Figure 4. In order to further reinforce the cellar casting and brace the same to prevent crushing or collapse thereof, which might otherwise occur, due to the tendency of the depending arms of the driving box to approach each other in service, a plurality of transversely extending depending bracing ribs 40 are provided on the bottom of the casting between each pair of lugs 32—32 and formed integral therewith. As clearly shown in Figures 2, 3 and 4, four such ribs are preferably employed, arranged in pairs, the members of each pair being spaced apart so as to accommodate the corresponding securing bolt 34 therebetween. With this arrangement, it will be observed that air is permitted to circulate both vertically between the pairs of corner lugs on each side of the casting and also longitudinally of the cellar, it being noted in this connection that the movable or displaceable plate 29 is made narrow so as to leave ample openings at either side thereof for the circulation of air lengthwise of the cellar.

The grease or other lubricant dispensed from the central chamber will be applied to the journal and carried around by the latter, and as the carried over or waste lubricant is brought down by the descending side of the journal, it will be collected in one or the other of the collecting chambers 13, depending upon the direction of rotation of the journal. Ordinarily, when grease is used as lubricant, it will be in a more or less solid state and will be deposited in the shallow chambers 13 and temporarily retained therein. As the waste lubricant is accumulated in the side chambers, the latter will fill and as more waste lubricant is collected, pressure will be set up in the retained waste lubricant so that, by providing a plurality of holes or vent openings 38—38, distributed over the bottoms of the collecting chambers, the lubricant which is in a plastic or semi-plastic state, will be expressed or extruded therethrough under pressure so that the grease cellar is self-clearing as will be obvious. As the waste grease or lubricant is expelled, it will drop down between the separated corner lugs of the cellar and thence to the roadway, thus obviating the necessity of attention to

the collection of waste grease or lubricant. The collected waste lubricant will also, after the cellar has been in use a very short time, provide a film or covering for the vent openings 38 so as to close the latter against the admission of dust that might otherwise possibly be forced upwardly therethrough and into contact with the journal.

The provision of a relatively narrow dispensing chamber permitting the use of a narrow grease cake, has been found to be very economical as compared with the more common grease cellars having a single wide chamber and correspondingly wide grease cake and dispensing plate.

It is further pointed out that my improved construction of grease cellar casting having air circulating passages assures adequate cooling of the same, thereby effecting a great reduction in the amount of lubricating agent consumed, without sacrificing strength, inasmuch as the transverse reinforcing ribs 40 between the lugs 32 thoroughly brace the casting against collapse, thus providing an exceptionally rugged construction which effectively prevents crushing of the cellar due to the tendency of the depending arms of the driving box to approach each other when the box becomes heated during operation in service.

With my improvements, it will be seen that the only attention that need be paid to the cellar is that of maintaining the supply of grease in the central chamber and this may be replenished by simply displacing the end plate 29 and without removing the grease cellar from the driving box.

Although I have herein shown and described what I now consider the preferred manner of carrying out my invention, the same is merely illustrative and I contemplate all changes and modifications that come within the scope of the claims appended hereto.

I claim:

1. A lubricating cellar for a locomotive driving box, said cellar having a dispensing chamber and a collecting chamber, the latter having spaced vent openings in a wall thereof leading to the exterior of the cellar through which the waste lubricant in a plastic state is adapted to be extruded.
2. A lubricating cellar for locomotive driving boxes, said cellar having a lubricant-dispensing chamber and a waste lubricant collecting chamber, the latter being open on its upper side with the opening presented to the journal and having a bottom wall provided at different zones with openings extending therethrough to the exterior of the cellar, whereby the collected waste lubricant is extruded while in a plastic state.
3. A cellar of the character described for locomotive driving boxes, said cellar having a central lubricant dispensing chamber and a collecting chamber on each side thereof, each

of said collecting chambers having a plurality of separated vent openings in a wall thereof leading to the exterior of the cellar and through which the collected waste lubricant is adapted to be discharged by extrusion while in a plastic condition.

4. A cellar of the character described for locomotive driving boxes, said cellar having a central relatively narrow, dispensing chamber and a relatively shallow collecting chamber on each side thereof, each collecting chamber being open at its top with the opening presented to the journal and having a bottom wall, the latter being perforated to provide discharge openings distributed throughout the same, leading to the exterior of the cellar to discharge the collected waste lubricant by extrusion while in a plastic condition, below said chamber.
- 10 5. A grease cellar for locomotive driving boxes comprising: a casting provided with a central dispensing chamber and shallow side collecting chambers and integrally formed corner attaching lugs, each of said side chambers being provided with a bottom wall with openings therein leading to the exterior of the cellar, said openings being distributed throughout the area of said wall whereby the waste grease in a plastic state collected 15 in said side chambers is adapted to be extruded through said openings.
- 20 30

In witness that I claim the foregoing I have hereunto subscribed my name this 17th day of May, 1927.
